CHARLES C. WORTHINGTON, OF DUNNFIELD, NEW JERSEY.

BUILDING-BLOCK.

1,400,709.

Specification of Letters Patent. Patented Dec. 20, 1921.

Application filed February 6, 1918. Serial No. 215,721.

To all whom it may concern:

Be it known that I, CHARLES C. WORTHINGTON, United States citizen, residing in Dunnfield, New Jersey, have invented the following described Improvements in Building-Blocks.

The invention consists in the structure of a composite building block comprising an organization of stonelike body walls suited to carry load and a softer material into which nails can be driven, both materials being specially combined to give maximum strength and stability to the wall constructed of such blocks while providing a maximum area of nailing surface on one or both sides of such wall to which furring and laths may be nailed and also providing a building element which can be cheaply and quickly made by ordinary methods and readily set up without the exercise of special care or skill.

In the accompanying drawings:

Figure 1 is a horizontal section through the preferred form of block indicating the relation of the furring and lath and plaster on opposite sides:

Fig. 2 a side elevation of a portion of a wall built of such blocks;

Fig. 3 a horizontal section of a modified form; and

Fig. 4 is an elevation of a portion of a wall constructed of the blocks of Fig. 3.

In Figs. 1 and 2 the body of the block is rectangular, about twice as long as wide, and formed with two equal adjacent rectangular cavities opening respectively on its opposite sides, each cavity being of a depth somewhat less than the thickness of the block and of such width and thickness as to make all the walls of the block of substantially uniform thickness throughout, especially the vertical walls, to wit the walls 1, 2 and 3 which extend transversely of the block and the walls 4 and 5 which extend longitudinally thereof. The top and bottom

walls are also desirably of the same thickness. Such block bodies may be made of an ordinary mixture of Portland cement and sand or of other fictile material having the requisite strength for building purposes.

The two cavities are filled flush with the edges with a nailing compound 6 which may be a mixture of cement, sand and wood sawdust or any other nailing compound of which several kinds are known to the trade, and this material may be introduced in any

suitable way, preferably by casting it therein in a plastic condition and allowing it to set. The blocks are then ready for use and may be laid up in quite the same manner as customary with hollow tile or other building blocks but keeping the exposed faces of the masses of nailing compound exposed on opposite sides of the wall. Each side of the resulting masonry wall will thus present substantially the appearance indicated in Fig. 2 wherein the nailing spaces are distributed uniformly and at frequent intervals over the entire area. Furring strips 7 can therefore be nailed to such a wall with great rapidity and with all the nails necessary for secure attachment to the mason work. They may be nailed to both sides of such a wall as indicated in Fig. 1 to give the usual air space, intervening between the blocks and the laths (8) on both sides.

In Figs. 3 and 4 the stone like block body is formed with cavities of the same character, but opening on the same side of the block thus providing the same number of vertical walls, 1, 2, 3, 4^a and 5^a all of uniform thickness, but exposing all the surfaces of the nailing material on the same side of the block. Where the exterior of the wall to be built is to be left plain or covered with stucco directly applied to it, these blocks may be used and laid up with all the nailing surfaces faced to the interior as indicated in Fig. 4 thus giving a larger proportion of nailing surface than indicated in Fig. 2 but with substantially the same strength of structure. In other cases these blocks may be laid up with the nailing surfaces of contiguous blocks faced in opposite directions as indicated in Fig. 3, thus dividing and distributing the total nailing surface equally between the opposite sides of the wall and giving substantially an equivalent extent of nailing surface to the form first described.

In both forms the block comprises a number of vertical, load-resisting walls each one of uniform thickness and a mass of nailing compound embraced on at least three sides by such walls and firmly seated or anchored therein or thereto. The vertical walls 1, 2 and 3 occur at frequent intervals in the constructed wall but are not alone depended on for carrying the vertical load inasmuch as the vertical back walls 4 and 5, and 4^a and 5^a, of the cavities can also carry a pro-

portionate share of the load, besides serving as bottoms to the cavities when receiving the nailing compound.

I am aware that it has heretofore been proposed to fill recesses in concrete and other objects with a soft material into which nails may be driven, but my invention is distinguished from such prior uses by the fact that it is a building block intended and adapted to be laid up with other similar blocks in a novel wall construction to provide uniformly distributed nailing surfaces over the whole of one or both sides of such wall according to preference and without involving any structural weakness in such wall by reason of the presence of the soft material representing the nailing compound and also because it possesses the various other characteristics set forth in the following claims:

1. As a new article of manufacture, a building block comprising a rectangular body of stonelike material cast with horizontal rectangular cavities formed by a plurality of vertical cross walls, which are disposed perpendicular to the face of the block and also by vertical longitudinal back walls forming the backs of the cavities, one of said vertical walls being a partition wall be-

tween adjacent cavities, each of said walls being of uniform thickness and a fistic nail-
ing material cast in position in each of said cavities to be exposed on the surface of the wall constructed of such blocks substantially as and for the purpose set forth. 30

2. The new article of manufacture set forth in claim 1 wherein the surfaces of the nailing material are exposed in opposite directions. 35

3. In building construction, a wall structure comprising assembled composite building blocks, each comprising a fistic stonelike material cast with vertical side and back walls forming a horizontally opening cavity and a fistic nailable material cast 45 in the cavity and exposed on the face of the block, the surfaces of such nailable material being of greater thickness than the thickness of the cavity side walls and being also disposed at regularly recurring intervals over the surfaces of the wall structure, vertically and horizontally, and adapting furring strips to be secured at random thereon by nailing into said surfaces. 50

In testimony whereof, I have signed this 55 specification.

CHARLES C. WORTHINGTON.
